UNITED STATES PATENT OFFICE.

CHRISTIAN M. HEINSEN, OF FRESNO, CALIFORNIA.

OIL-BURNER.

1,160,404.

Specification of Letters Patent. Patented Nov. 16, 1913.

Application filed April 22, 1914. Serial No. 833,700.

To all whom it may concern:

Be it known that I, CHRISTIAN M. HEINSEN, a citizen of the United States, residing at Fresno, in the county of Fresno, State of California, have invented certain new and useful Improvements in Oil-Burners; and I do hereby declare the following to be a full, clear, and exact description of the invention, such as will enable others skilled in the art 10 to which it appertains to make and use the same.

This invention relates to oil burners.

The object of the invention resides in the provision of an oil burner which embodies 15 an improved construction for finely dividing the oil and mixing same thoroughly with a suitable quantity of steam previous to the passage of the oil to the burner tip.

A further object of the invention resides 20 in the provision of an oil burner so constructed and arranged that oil can be delivered to the burner by gravity alone, thus eliminating the use of a pump for supplying oil to the burner.

25 A still further object of the invention resides in the provision of an oil burner to which oil is delivered by gravity and which embodies an improved construction for preventing back pressure on the oil so delivered.

30 With the above and other objects in view the invention consists in the details of construction and in the arrangement and combination of parts to be hereinafter more fully described and particularly pointed out 35 in the appended claim.

In describing the invention in detail reference will be had to the accompanying drawings wherein like characters of reference denote corresponding parts in the several 40 views, and in which

Figure 1 is a plan view of an oil burner constructed in accordance with the invention; Fig. 2, a vertical section of what is shown in Fig. 1. Fig. 3, a section on the 45 line 3—3 of Fig. 1; and Fig. 4, a perspective view of the fan wheel employed in the burner.

Referring to the drawings the burner is shown as comprising a tubular body portion 10 which is threaded at one end for the

reception of a burner tip as at 11. The body portion 10 is enlarged intermediate its ends to form a fan chamber 12, the bore of the body 10 communicating with said fan chamber at the upper end of the latter. The 50 chamber 12 opens through one side of the body 10 and is closed through the medium of a cap 13 threaded in the body, said cap having a central opening 14 provided with threads 15. Secured to the inner side of the 55 cap 13 is a bridge bearing 16 extending transversely of the opening 14. Rotatably mounted in the bearing 16 and in the opposite side of the body 10 is a shaft 17 upon which is fixed a fan A. This fan includes a hub portion 18 and a plurality of radial blades 19, the outer ends of said blades being provided with lateral extensions 20 directed toward the cap 13. Engaged with the threads 15 is one end of an oil supply pipe 70 21 leading from a suitable oil supply disposed above the burner whereby oil may be supplied by gravity. Threaded in the bore of the body 10 at the end thereof remote from the end which carries the burner tip 75 is a steam supply pipe 22 provided with a nozzle 23 positioned to discharge against the blades 19 at the top of the chamber 12.

In the operation of the burner steam is turned into the pipe 22 from whence it passes through the nozzle 23 against the blades 19. At the same time oil is delivered into the chamber 12 from the pipe 21 at the center of the fan wheel A. This oil is heated and partly vaporized by the steam 80 and the rotation of the fan wheel will break up the oil and thoroughly mix same with the steam so as to produce a highly combustible mixture for delivery to the burner tip. 90

What is claimed is:—

An oil burner comprising a tubular body having an enlarged portion forming a fan wheel chamber interrupting the bore of the body, a steam pipe mounted in one end of the bore of the body, a fan wheel rotatably mounted in said chamber and including blades against which the steam pipe discharges, said blades being provided respectively with cutaway portions adjacent the 95 100

axis of the fan and opening through the sides of the blades, and an oil pipe delivering into said chamber at right angles to the bore of the body and in line with the axis of the fan and on the side of the fan through which the cutaway portions of the blades open.

In testimony whereof, I affix my signature, in the presence of two witnesses.

CHRISTIAN M. HEINSEN.
